FLOATING GRID GATES

Thomas A. Coffee, Las Cruces, N. Mex., assignor to the United States of America as represented by the Secretary of the Army

Filed Feb. 11, 1960, Ser. No. 8,202

6 Claims. (Cl. 328—94)

(Granted under Title 35, U.S. Code (1952), sec. 266)

The invention described herein may be manufactured and used by or for the Government for governmental purposes without the payment of royalty thereon.

This invention relates generally to electron tube circuits, and more particularly to a floating grid electron tube circuit.

In the usual practice of the art, electronic devices which depend upon maintaining a certain bias point in their operation are very critical in adjustment and are adversely effected by aging variations in signal input and power supply fluctuations. It is, therefore, highly desirable to obtain a circuit which is stable in time despite signal variations, and power supply changes; and it would be further highly advantageous to have such a circuit self-adjusting. Accordingly, it will be seen that this invention fulfills these needs in many applications.

A general object of this invention is to provide a device which utilizes an input signal to produce a determining potential usable in the modification of input signals.

It is a more specific purpose of this invention to provide a self-adjusting highly stable coincidence circuit.

It is a further object of this invention to provide a self adjusting, self-determined highly stable gate circuit.

In accordance with this invention an electron tube device is constructed utilizing a positive-signal-developed negative grid potential bias to control electron flow between a negative cathode and a positive plate, the control potential being, by its nature, of such a magnitude as to permit the passage of only a determined portion of further signals. The grid is connected to one or more sources through isolating capacitance, and having no direct ground return path. The device may have a cathode load, a plate load, or both. A pulse, positive with respect to cathode, when coupled between the input side of the grid capacitance and cathode, will cause the capacitance to draw grid current until the capacitance becomes charged. This charge, which will equal in magnitude the voltage potential of the input pulse, will remain as a negative bias on the grid for a period which is limited only by the insulating properties of the capacitance and associated electron tube. In effect, the positive peak of the input signal (a composite signal if more than one signal is used) is clamped to contact bias (floating grid bias without signal) and the output of the tube responds to that part of the signal extending from the positive peak of the signal downward, in a negative direction, in an amount equal in magnitude to cutoff bias for the particular cathode-anode potential employed. The cutoff point of the tube will then serve to clip any portion of the bottom of the signal which extends below cutoff. In the case in which two or more simultaneous signals are presented, the bias value is approximately equal to the negative sum of the positive value of signal one plus signal two, etc. for as many signals as are presented. In this case one signal may be used to raise the grid level up to cutoff, thus allowing the other signal or signals to be fully reproduced. This type of action is commonly referred to as "gating" in the concerned art.

These and other features and objects of this invention will be more readily understood from the following description read in conjunction with the drawings in which:

FIGURE 1 is a schematic diagram showing a general purpose form of the invention;

2

FIGURE 2 is a schematic diagram showing a second, more specialized form of the invention.

FIGURE 3 shows certain coincident waveforms as are found at certain places in an embodiment of the invention;

FIGURE 4 shows a third embodiment of the invention.

From FIGURE 1, it can be seen that electron tube 3 is a conventional triode, having grid 4, emitting cathode 5 and anode 6, said anode being connected to an anode load resistance 7. Connected to the grid 4 are capacitances 8 and 9. FIGURE 2 shows the same configuration of the invention with the exception that anode load 7 has been omitted and cathode load 10 has been substituted. The circuit inputs are represented by waveforms 11 and 12, in both figures, while waveform 13 represents the output of the circuit in FIGURE 1, and 14 represents the output of the circuit shown in FIGURE 2. FIGURE 3 gives a simultaneous representation of the signal input to be gated, 11, the gating pulse 12, the grid voltage 20, and the output 13 of the circuit of FIGURE 1.

In operation, the tube 3 draws current from the cathode 5 through the anode 6 and the load resistor 7. A positive signal 11 from source 16 is capacitively coupled to grid 4 via capacitor 8 causing the grid to become positive with respect to the cathode. Electrons are immediately drawn from the cathode 5 to the grid 4 and to the plate 6. Current flows and the signal 11 from source 16 appears in the output of tube 3. Since there is no fixed or applied bias (the circuit having no D.C. path from grid 4 to ground) a cathode 5 to grid 4 electron flow will take place during conduction of the tube until the tube reaches its natural state of equilibrium, at which time the grid will have stabilized at the contact potential point of the tube (normally just positive +0.2 to +0.7 volt). The tube will continue to conduct after reaching contact potential and the signal 11 from source 16 will continue to appear in the output.

If another positive signal 12 from source 17, is simultaneously yet non-coincidentally applied to grid 4 via capacitor 9, then both the signals from source 16 and 17 will appear in the output without noticeable change in the tubes operation. Electron flow from cathode 5 to grid 4 will have once again occurred until the grid 4 is stabilized at the contact potential of the tube.

When a first coincidence of signals from source 16 and source 17 occurs the additive effect of the simultaneous positive potentials on both capacitors 8 and 9 causes the grid 4 to again go positive with respect to cathode 5. Again electrons flow from cathode 5 to grid 4 as the tube conducts and the grid 4 again stabilizes at contact potential as its positive charge is mostly neutralized by electrons flowing from the cathode.

Since this electron flow from cathode 5 to grid 4 which occurs when the tube is conducting, is not reversible, removal of the coincidental existance of signals from sources 16 or 17, or both will not affect the negative charge on grid 4 (now equivalent to the sum of the signals 11 and 12) which will hold the tube so far below cut-off that neither signal 11 nor 12 applied alone, nor together but not in coincidence, can cause the tube to conduct. After the first coincidence only a further coincidence will appear as a signal in the output 13, hence gating action occurs.

FIGURE 2 shows an embodiment in which a cathode output is utilized in order to obtain a positive pulse, rather than the negative pulse obtained from the circuit of FIGURE 1.

FIGURE 4 shows a circuit in which the signals are applied via only one capacitor 15 and wherein the internal impedances of the two signal sources 16 and 17 are represented by resistances R₁₆ and R₁₇, respectively. Operation is, in this case, identical with the foregoing,

with the exception that the signals are combined previous to their application to the capacitor.

Those skilled in the art will appreciate that the objects of this invention are met by the utilization of a novel floating grid vacuum tube circuit in an unusual mode of operation. It will be further appreciated by those skilled in the art, that the device set forth herein provides a more stable, highly dependable coincidence circuit than has been heretofore possible.

The principle of the invention explained in connection with specific exemplification thereof will suggest many other applications and modifications of the same. A partial list of these would include amplitude selection, diode switching for position signals, time selections, multigrid switching, multiple coincidence operation, adjacent time selection, time demodulation, and sync separation. Most of these applications, and others for which the present invention may be advantageously employed, are treated in volume 19 of the Radiation Laboratory Series, particularly chapter 10. It is accordingly desired that, in construing the breadth of the appended claims, they shall not be limited to the specific details shown and described in connection with exemplifications thereof.

Therefore what is claimed and it is desired to secure by Letters Patent of the United States is:

I claim:

1. An electron tube circuit comprising a vacuum tube having at least one anode, at least one cathode and at least one grid, said anode being connected through an impedance element to a source of voltage positive in relation to said cathode, said grid being direct current isolated from said anode and said cathode, a capacitive input element connected to said grid, a pair of signal sources being connected in parallel between said cathode and said input element.

2. An electron tube circuit comprising a vacuum tube having at least one anode, at least one cathode, and at least one grid, said anode connected to a source of voltage positive in relation to said cathode, said cathode connected through a resistive element and said source to said anode, said grid being direct current isolated from said anode and said cathode, a capacitive input element connected to said grid, a pair of signal sources connected in parallel between said input element and said voltage source.

3. An electron tube gating circuit comprising a vacuum tube having at least one anode, at least one cathode and at least one grid, said anode being connected

5 to a source of voltage positive in relation to said cathode, a capacitor connected to said grid, a signal source, a control potential source, said grid being direct current isolated from said anode and said cathode, said grid being connected through a parallel connection of said signal source and said control potential source to said cathode.

4. An electron tube circuit comprising a vacuum tube having at least one anode, at least one cathode and at least one grid, said anode being connected to a source of voltage positive in relation to said cathode, said grid being direct current isolated from said anode and said cathode, a plurality of signal sources and a plurality of capacitors, each of said sources being connected to said cathode and through separate said capacitors to said grid.

5. A circuit comprising a vacuum tube having a grid, a cathode, and an anode, a pair of capacitors connected in parallel and to said grid, said grid thereby being direct current isolated from said cathode and said anode, a pair of pulsing sources each connected between a respective one of said capacitors and said cathode, a substantially constant voltage source, and a resistance connected between said constant voltage source and said anode, whereby an output signal proportional to one of said pulsing sources and controlled by the other of said pulsing sources is developed across said resistance.

6. A circuit comprising a vacuum tube having a grid, a cathode and an anode; a voltage source; a plurality of pulsing means and a plurality of capacitors connected in parallel lines between said grid and said cathode, each of said lines including one of said pulsing means and one of said capacitors said grid thereby being direct current isolated from said anode and said cathode; and a resistance connected in series with said voltage source, said anode, and said cathode; whereby an output signal proportional to one of said pulsing means and controlled by the other of said pulsing means is developed across said resistance.
